Inventor

Blanchard V. Kirk

United States Patent Office.

BLANCHARD V. KIRK, OF PHILADELPHIA, PENNSYLVANIA, ASSIGNOR TO
HIMSELF AND H. A. MUSSELMAN, OF SAME PLACE.

Letters Patent No. 69,222, dated September 24, 1867; antedated September 11, 1867.

IMPROVEMENT IN SKIRT-ELEVATORS.

The Schedule referred to in these Letters Patent and making part of the same.

TO ALL WHOM IT MAY CONCERN:

Be it known that I, BLANCHARD V. KIRK, of Philadelphia, in the county of Philadelphia, and State of Pennsylvania, have invented a new and useful "Skirt-Elevator;" and I do hereby declare the following is a full, clear, and exact description thereof, reference being had to the accompanying drawings, and to the letters of reference marked thereon.

The nature of my invention consists in a device to be attached to a lady's waist, by which her dress may be looped up or festooned, so as to raise the lower edge from the ground out of the mud and dirt.

To enable others skilled in the art to make and use my invention, I will proceed to describe its construction and operation.

Figure 1 is a plan.

Figure 2 is a cross-section.

Figure 3 is an elevation.

Figure 4 is the clasp in detail.

A is a tube, about five-eighths of an inch in outside diameter, formed of India rubber, or other elastic material, which can be bent in a circular form to fit the waist of the wearer. I prefer India rubber, as it is slightly elastic lengthwise, as well as bendable, and the same ring will stretch so as to fit different persons. This tube has at intervals, on its lower and outer edge, holes B, fig. 2, with eyelets riveted in the said holes. This riveting is done by means of a long rod inserted through the tube. This rod has on it a small turned conical nipple fitting into the eyelet. The ends of the tube are capped with ferrules, C and C', which are sewn to it, as shown in fig. 4, at e. One of these ferrules, C, has a notch, g, cut in it, and the other one, C', has a square pin which fits into the said notch g, thus forming a clasp, by which the two ends of the tube are secured on the person; or one ferrule might have a hook and the other an eye, which would answer the same purpose as the plan shown. On the lower and outer side of these ferrules are two holes, h h, through each of which four cords k are passed, and are united in tassels L L, fig. 1. The other ends of the cords pass inside of the tube A, and one cord passes out through each eyelet B and terminates in a hook or button L. To make the ring A more convenient to handle, and ornamental, it is covered with colored silk or wool woven on, as shown, fig. 1, in red lines, where one-half is shown covered with red wool, the other being without it. If the material is loosely woven it will stretch slightly with the tube.

Fig. 3 shows a lady's dress, N, looped up by this device. Eyes are sewn on the dress at the part marked l l, a few inches from the bottom, to which the hooks l are fastened. Then, by drawing the cords k and tying them in a bow, the lower part of the dress is kept raised from the ground. This device may be worn either inside or outside of the dress, whichever is preferred. The cords k being passed inside a ring, as described, are prevented from the friction they would have if exposed.

To use my invention choose one a little smaller than the waist it is to be worn upon, and having clasped it round above the hips, fasten the hooks L into their corresponding eyes on the dress, the tassels L hanging outside in front. When it is desired to elevate the dress the tassels are pulled, and the cords k tied in a bow in front.

What I claim as my invention, and desire to secure by Letters Patent, is—

I claim the combination of the India-rubber tube A, covered with a woven fabric, m, provided with tubular clasps C C', having openings h h, through which pass the cords k, the whole constructed and operating substantially as described.

BLANCHARD V. KIRK.
